UNITED STATES PATENT OFFICE

111,986

DESIGN FOR A CAMERA OR SIMILAR ARTICLE

James D. Milne, Pittsfield, Mass., assignor, by
mesne assignments, to Universal Camera Cor-
poration, a corporation of New York

Application June 19, 1934, Serial No. 52,239

Term of patent 3½ years

To all whom it may concern:

Be it known that I, James D. Milne, a citizen
of the United States, residing at Pittsfield, in the
county of Berkshire and in the Commonwealth
of Massachusetts, have invented a new, original,
and ornamental Design for a Camera or Similar
Article, of which the following is a specification,
reference being had to the accompanying draw-
ings, forming part thereof.

In the drawings, Fig. 1 is a side elevational
view of a camera or similar article embodying
my new design; Fig. 2 is a top plan view; Fig. 3
is a front elevational view; and Fig. 4 is a rear
elevational view.

What I claim is:

The ornamental design for a camera or similar
article, substantially as shown.

JAMES D. MILNE.
